(57) **CLAIM**

The ornamental design for a packaging container having surface ornamentation, as shown and described.

DESCRIPTION

FIG. 1 is a perspective view of a packaging container having surface ornamentation embodying our new design;

FIG. 2 is a front view thereof;
FIG. 3 is a rear view thereof;
FIG. 4 is a right side view thereof;
FIG. 5 is a left side view thereof;
FIG. 6 is a top view thereof;
FIG. 7 is a bottom view thereof;
FIG. 8 is a perspective view of a second embodiment of packaging container having surface ornamentation embodying our new design;
FIG. 9 is a front view thereof;
FIG. 10 is a rear view thereof;
FIG. 11 is a right side view thereof;
FIG. 12 is a left side view thereof;
FIG. 13 is a top view thereof;
FIG. 14 is a bottom view thereof;
FIG. 15 is a perspective view of a third embodiment of packaging container having surface ornamentation embodying our new design;
FIG. 16 is a front view thereof;
FIG. 17 is a rear view thereof;
FIG. 18 is a right side view thereof;
FIG. 19 is a left side view thereof;
FIG. 20 is a top view thereof;
FIG. 21 is a bottom view thereof;
FIG. 22 is a perspective view of a fourth embodiment of packaging container having surface ornamentation embodying our new design;
FIG. 23 is a front view thereof;
FIG. 24 is a rear view thereof;
FIG. 25 is a right side view thereof;
FIG. 26 is a left side view thereof;
FIG. 27 is a top view thereof;
FIG. 28 is a bottom view thereof;
FIG. 29 is a perspective view of a fifth embodiment of packaging container having surface ornamentation embodying our new design;
FIG. 30 is a front view thereof;
FIG. 31 is a rear view thereof;
FIG. 32 is a right side view thereof;
FIG. 33 is a left side view thereof;
FIG. 34 is a top view thereof; and,
FIG. 35 is a bottom view thereof.

Broken lines are included herein for illustrative purposes only and form no part of the claimed design.
